UNITED STATES PATENT OFFICE.

LUTHER L. KNOX, OF AVALON, PENNSYLVANIA, ASSIGNOR TO BIAW-KNOX COMPANY,
OF PITTSBURGH, PENNSYLVANIA, A CORPORATION OF NEW JERSEY.

REVERSING-FURNACE.

1,351,915.

Specification of Letters Patent.

Patented Sept. 7, 1920.

Application filed December 21, 1916. Serial No. 138,289.

To all whom it may concern:

Be it known that I, LUTHER L. KNOX, a citizen of the United States, residing at Avalon, Allegheny county, Pennsylvania, have invented a new and useful Improvement in Reversing-Furnaces, of which the following is a full, clear, and exact description, reference being had to the accompanying drawings, forming part of this specification, in which:

Figure 1 is a plan view of a valve system embodying my invention, showing the several flues controlled by the valves in dotted lines.

Fig. 2 is a side elevation of the valve system, and showing some of the flues in vertical section.

Fig. 3 is a section on the line III—III of Fig. 1.

Fig. 4 is a detail view showing one of the valve structures and its actuating connections, and

Fig. 5 is a side elevation of one of the motors and its gear connections.

My invention has relation to a valve system for reversing regenerative furnaces, and is designed to provide a system of this character in which the several air and gas valves are mechanically actuated by means of motors, each motor operating one set of valves, and whereby, by proper control of the motors, the valves may be operated in certain predetermined time relations. A further object of the invention is to provide a system of this character in which the actuating connections for the gas inlet control valves and the gas and air reversing valves are provided with means whereby the valves of each set may be operated in a predetermined relation.

The nature of my invention will be best understood by reference to the accompanying drawings, in which I have shown a preferred embodiment thereof, and which will now be described, it being premised, however, that various changes can be made in the details of construction and arrangement of the parts without departing from the spirit and scope of my invention as set forth in the appended claims.

In these drawings the numeral 2 designates the gas regenerator at one end of the furnace, and 2^a the gas regenerator at the opposite end of the furnace. 3 is an air re-

generator at one end, and 3^a a similar regenerator at the opposite end. 4 designates a gas inlet flue leading to the regenerator 2 and 4^a a gas inlet flue leading to the regenerator 2^a. 5 designates the air inlet flue for the regenerator 3, and 5^a the corresponding air inlet flue for the regenerator 3^a. 6 is the gas inlet control valve for the flue 4, and 6^a the similar valve for the flue 4^a. 7 is a gas reversing valve placed in a flue 8 leading to a stack flue 9; and 7^a is a similar gas reversing valve placed in a flue 8^a also leading to the stack connection 9. 10 is the air inlet valve for the flue 5, and 10^a a similar valve for the flue 5^a. 11 is the air reversing valve for the flue 5, and 11^a a similar valve for the flue 5^a.

The valves 6, 6^a, 7, 7^a, and 11, 11^a are shown as being of the damper type and are preferably set so as to seat obliquely across their respective flues. The air inlet valves 10 and 10^a are shown as being of the mushroom type and provided with seats at the mouths of the respective air inlets. The particular character and details of construction of the several valves form no part whatever of the present invention.

12 designates an electric motor whose armature shaft is connected through suitable gearing 13 with a shaft 14, having thereon a double pulley 15 (see Figs. 1, 3 and 5). Connected to one member of the pulley 15 at one end is a cable 16 which extends over suitable guide pulleys 17 and thence downwardly, being connected at its opposite end to the air reversing valve 11. 12^a A similar cable 16^a is connected to the other member of the pulley 15 and extends thence over the guide pulleys 17^a and is connected at its other end to the air reversing valve 11^a. Hung from the cable 16 between the pulleys 15 and 17 is a movable counterweight 18; and 18^a is a similar counterweight hung on the cable 16^a. The shaft 14 also carries two pulleys 19 and 19^a. Connected to the pulley 19 at one end is a cable 20 which extends over a guide pulley 21 and thence downwardly and is connected to a weighted yoke 22 which has a sliding lost motion connection with the headed stem 23 of the air inlet valve 10. 20^a is a similar cable connected at one end to the pulley 19^a and thence passing over a guide pulley 21^a and being connected to the stem 23^a of the valve

10 through the medium of the yoke 22^a. Each guide pulley 21, 21^a is mounted on a pivoted arm 24 or 24^a. Each of these levers has an actuating connection 25 or 25^a with an actuating screw 26 or 26^a. By means of these screws and connections, the extent of opening of the valves 10 and 10^a may be regulated. These connections also provide means whereby the valves 10 and 10^a may be 5 opened and closed manually, if desired. There is sufficient play in the lost motion connection between the yoke and the stem of each of these valves so that by actuating the screw 26 or 26^a the valve 10 or 10^a may 10 be set to a position in which it will remain seated, irrespective of the position of the corresponding air reversing valve 11 or 11^a, as may be desirable in blowing out the flues. 15

27 is a second electric motor which is connected by gearing 28 (similar to that described in connection with motor 12) with a double pulley 29. This pulley is connected by the oppositely winding and extending cables 30 and 30^a with the respective gas reversing valves 7 and 7^a. 31, 31^a designate suitable guide pulleys for these cables 30 and 30^a. Each of these cables is also provided with a suspended movable counterweight 32 or 32^a, similar to the counterweights 18 and 18^a before described. 20

33 designates a third electric motor which is connected by gearing 34 with a shaft carrying a double pulley 35. This pulley 35 is connected by oppositely winding and 25 extending cables 36 and 36^a with the respective gas inlet control valves 6 and 6^a. 37 and 37^a designate guide pulleys for the cables 36, 36^a. 38 and 38^a designate suspended counterweights for the cables 36 and 36^a, 30 these being similar to the counterweights for the other cables before described. 40

The shafts of the main guide pulleys 17, 17^a, 31, 31^a, and 37, 37^a are each provided with another pulley 39; and connected to 45 each pulley 39 is a cable 40 which extends upwardly over a guide pulley 41 and thence downwardly to a counterweight 42. The end portion of each cable 40 is provided with adjustable stops 43 for engagement with the 50 lever arm 44 of an electric switch device 45, this switch being suitably connected with the circuit of the electric motor which controls the particular valve, the movement of which actuates the cable 40. The purpose of 55 these limit switches is to automatically stop the motor after the desired amount of movement of the valve. Each counterweight 42 is also provided with an indicator 46. These indicators provide means whereby the operator 60 can, at a glance, determine the position of each of the valves.

The operation of the reversing valves will be readily understood. It will be seen that when each motor is actuated one set of the 65 damper valves will be operated to open one

valve and close the other; and that the operation of the motor 12 will also effect the opening of one of the air inlet valves and the closing of the other air inlet valve. By reason of the counterweights with which the 70 actuating connections for the damper valves are provided it will be readily seen that each motor will operate to close one of the damper valves actuated by it, or substantially close it, before the other damper valve of that 75 set will start to open. Thus, considering the valves 11 and 11^a in Fig. 3, it will readily be seen that the operation of the pulley 15 will immediately slack the cable 16 to permit the valve 11 to close; but that before the 80 valve 11^a can start to open, the counterweight 18^a on the cable 16^a must be raised and all the slack on which said counterweight hangs be taken up.

It will therefore be apparent that at each 85 reversal the air and gas controlling valves for one end of the furnace, together with the gas inlet control valve for that end of the furnace, will be closed before the corresponding valves for the opposite end of the 90 furnace start to open. This arrangement is designed to reduce to a minimum the loss of gas at each reversal.

The several motors may be operated in any predetermined time relation by suitable 95 connections and switches, such a system of operation being described and claimed in my pending application Serial No. 108,130, filed March 10, 1916.

For instance, supposing the valves to be 100 in the positions shown in Figs. 1, 2 and 3, and the valves 6^a and 10^a are open, and the valves 7^a and 11^a are closed at one end of the furnace, while at the other end of the furnace valves 6 and 10 are closed and 105 valves 7 and 11 are open, and it is desired to reverse the furnace, this is preferably accomplished as follows: The valve 6^a is first closed. After a proper time interval the valves 7^a and 11^a will be opened and the 110 valve 10^a will be closed. Valve 10 will be opened at about the time that valve 10^a is closed. There will be a time interval between the opening of valve 7^a and the closing of valve 7, and valve 6 will be the last 115 to open. In this manner, any gas trapped between the valve 6^a and the furnace at the time valve 6^a is closed, will be burned before the reversal is effected.

My invention provides a valve operating 120 system in which the work of reversing the valves is positively and reliably performed by means of power motors. By means of the described indicators, the operator can at once detect any failure of any valve to 125 properly operate from any cause.

It will be readily understood that the details of construction and arrangement of the various actuating connections, as well as the construction and character of the 130

valves themselves, may be widely varied within the spirit and scope of my invention as defined in the claims.

I claim:

- 5 1. A valve system for furnaces, comprising a pair of air-inlet-valves, a pair of air reversing valves, a pair of gas inlet valves, and a pair of gas-reversing valves, a motor having actuating connections with the air inlet and the air reversing valves, a second motor for the gas inlet valves, and a third motor for the gas-reversing valves, said motors being arranged for independent actuation; substantially as described.
- 10 15 2. A valve system for furnaces, comprising a pair of air-inlet-valves, a pair of air reversing valves, a pair of gas inlet valves, and a pair of gas-reversing valves, a motor having actuating connections with the air inlet and the air reversing valves, a second motor for the gas inlet valves, and a third motor for the gas-reversing valves, said motors being arranged for independent actuation, the actuating connections between each
- 20 25 motor and the pair or pairs of valves controlled thereby being arranged to move one valve of each pair in advance of and in the

reverse direction to the other one of the particular pair; substantially as described.

3. A valve system for furnaces, comprising a pair of air-inlet-valves, a pair of air reversing valves, a pair of gas inlet valves, and a pair of gas-reversing valves, a motor having actuating connections with the air inlet and the air reversing valves, a second motor for the gas inlet valves, and a third motor for the gas-reversing valves, said motors being arranged for independent actuation, the actuating connections between each motor and the pair or pairs of valves controlled thereby being arranged to move one valve of each pair in advance of and in the reverse direction to the other one of the particular pair, together with means actuated by said connections for indicating the position of a number of the said valves; substantially as described.

In testimony whereof, I have hereunto set my hand.

LUTHER L. KNOX.
